UNITED STATES PATENT OFFICE.

JOSEPH LÉON GOBEILLE, OF CLEVELAND, OHIO.

DESIGN FOR A COOK-STOVE.

SPECIFICATION forming part of Design No. 16,201, dated August 11, 1885.

Application filed May 6, 1885. Term of patent 7 years.

To all whom it may concern:

Be it known that I, JOSEPH LÉON GOBEILLE, of the city of Cleveland, in the county of Cuyahoga and State of Ohio, have invented a new and original Design for Cooking-Stoves; and I hereby declare that the following is a specification of the said new design, reference being had to the accompanying cut, print, or photograph.

10 This design embraces several new and distinctive parts and combinations of parts which go to make up the whole design, as hereinafter specified.

One integral part of this design is the shape 15 and ornamentation of the oven-door G, the same being of the form shown, with swelling surface A, and the ornamentation thereof consisting of the raised upright branch and bloom a on the end of said swelling surface A. Another 20 distinct part is the raised compound ornament b along the bottom of said surface A, having a raised rosette, c, in the center. Another distinct part is the upright straight raised lines d d' at right angles with the horizontal 25 straight raised lines e e'. Another distinct part is the raised conventional blooms f f', displayed in the space above the name-plate B. Another distinct part is the raised inclined branch g. Another distinct part is the quarter-rosette h in the angle of the lines d and e'. Another 30 distinct part is the scroll h' at the end and depending from the line e', all as shown.

A further distinctive part of this design is 35 the shape and ornamentation of the rear extension-plate, C, the same being of the form shown, and the ornamentation consisting of the raised rectangular panel D, with the raised rosette i in the center thereof, the upright 40 raised branches j j' on either end thereof, and the raised rosettes k k' k'', one in each corner thereof, the upturned half-rosette l in the upper part thereof, and the downturned half-rosette l' in the lower part thereof.

45 Another distinctive feature of the ornamentation of the rear extension-plate, C, is the serrated edge m, the rosette n above the rear end thereof, and the inclined branch o, with the quarter-rosette p above it, all as shown.

A further distinctive part of this design is 50 the shape and ornamentation of the side fire-door, F, all of which is in general the same as that of the panel D, as shown.

A further distinctive part of this design is 55 the shape and ornamentation of the front door, E, the same being of the form shown, and consisting of the upward beveled upper part, H, ornamented with rosettes q q', displayed on either end thereof, and the row r of blooms, overlapping each other, displayed between the 60 rosettes q and q', and the flat upright lower portion, s, ornamented with upright sprays t t' t'' t'', displayed thereon, and having upon the edge thereof the raised ornament with regular serrate edge or outline u, all as shown. 65

The whole design embraces the shape and ornamentation of the oven-door G, the extension C, side fire-door, F, and the front door, E.

I claim as new—

1. In a design for a cooking-stove, the oven-door G, consisting of the parts a b c d d' e e' f f' g h h', all having the shape and ornamentation as shown and described. 70

2. In a design for a cooking-stove, the extension-plate C, consisting of the parts D i j j' 75 k k' k'' l l' m n o p, all having the shape and ornamentation as shown and described.

3. In a design for a cooking-stove, the side fire-door, F, consisting of the parts i j j' k k' k'' l l', all having the shape and ornamentation as shown and described. 80

4. In a design for a cooking-stove, the front door, E, consisting of the parts H q r s t t' t'' t'' u, all having the shape and ornamentation as shown and described. 85

5. The design for a cooking-stove, embracing the oven-door, the extension-plate, the side fire-door, and the front door, all shaped and ornamented substantially as shown and described. 90

In testimony whereof I hereunto set my hand, in the presence of two subscribing witnesses, this 23d day of April, 1885.

JOSEPH LÉON GOBEILLE.
